UNITED STATES PATENT OFFICE.

GUSTAV JOHNSON, OF WEST ROXBURY, MASSACHUSETTS, ASSIGNOR TO CARR FASTENER COMPANY, OF CAMBRIDGE, MASSACHUSETTS, A CORPORATION OF MAINE.

SEPARABLE FASTENER.

Application filed December 20, 1924. Serial No. 757,152.

This invention aims to provide an improved separable fastener.

In the drawings, which illustrate a preferred embodiment of my invention:—

5 Figure 1 is a front elevation of the preferred form of fastener;

Fig. 2 is a section on the line 2—2 of Fig. 1;

Fig. 3 is a rear elevation of the one-piece socket attached to its support;

10 Fig. 4 is an elevation view of the socket having the support removed;

Fig. 5 is a section on the line 5—5 of Fig. 4; and

15 Fig. 6 includes a side and a rear elevation of the socket before it is attached to its support.

Referring to the drawings, I have shown a snap fastener which includes a simple, inexpensive and durable socket formed from a 20 single piece of metal. Heretofore separable fastener socket installations usually included at least two parts, the socket part and the clench plate, especially in socket installations where the head of a stud is concealed from view when the socket is secured to the stud. While in some instances, the socket installation must of necessity comprise more than one metal part, I have found that a socket installation of the type mentioned above, 25 may be satisfactorily formed from a single piece of metal without loss of durability or fastening qualities.

The novel construction of a one-piece socket installation, as illustrated by the drawings, comprises a cap portion 1 located at the front face of the carrying medium 2, a stud-receiving aperture 3, presented at the back face of the carrying medium, and a plurality of attaching portions 4 adjacent the stud-receiving aperture 3. The stud-receiving aperture 3 may be of fixed dimensions for reception of a resilient stud but I prefer to provide a plurality of resilient jaws 5 which surround the aperture and cooperate with a stud of fixed dimensions, as illustrated.

45 In forming the socket, I first stamp out a piece of metal to present a plurality of petal-like projections which, when the socket is

completely formed, comprise the gripping surface 6 adjacent the carrying medium, the 50 jaws 5 and the attaching portions 4, as best illustrated in Figs. 2 and 4. The center or cap portion 1 of the socket is preferably spaced away from the gripping surface 6 to permit expansion and contraction of the resilient jaws 5. These petal-like projections extend from the periphery of the cap portion 1 (Fig. 5) inwardly, upwardly through the curtain and then outwardly over the inner face of the curtain, the jaws comprising those 55 portions of the projections between the inner and outer surfaces of the fabric 2.

Normally, the attaching portions 4 extend parallel with the axis of the socket so that they may pass through an aperture 7 in the carrying medium to be presented at the back face thereof. They are then bent outwardly and downwardly so that they lie against the face of the carrying medium and spread over a substantial portion thereof for securing the 60 socket to the socket-carrying medium.

The stud, as illustrated, includes a head 8, a neck 9 and a base portion 10 and is secured to a flexible carrying material 11 by a tubular attaching rivet 12, as shown in Fig. 2

65 When the stud and socket are being engaged, the head 8 of the stud is forced between the jaws 5, which, with the attaching portions 4 expand or spread to permit passage of the head and thereafter to grip the neck 9 of the stud (Fig. 2). Thus the stud and socket are held securely together and the carrying mediums 2 and 11 lie so close together that the stud and socket cannot be separated by lateral strain exerted upon the carrying 70 75 mediums in opposite directions.

80 Separation of the fastener is preferably effected by an outward pull on one of the carrying mediums, while the other is held.

85 While I have shown and described a preferred form of my invention, it will be understood that I have done so merely for clarification, and that my invention is best defined in the following claim.

90 I claim—

95 A one-piece socket secured to a support

and presenting a pre-formed continuous cap member at one side of the support a plurality of relatively long, narrow, attaching fingers 5 pressed directly against and extending over a substantial portion of the opposite side of the support and being in contact with the support throughout the entire length of the attaching portions of said fingers and a plurality of neck-engaging jaws provided by said

fingers between the attaching portions thereof and the cap, said jaws and said attaching fingers being expansible to permit passage of the head of a stud between said neck-engaging jaws. 10

In testimony whereof, I have signed my 15 name to this specification.

GUSTAV JOHNSON.
